UNITED STATES PATENT OFFICE

159,735

GAME BOARD

Alfred H. Keast, San Francisco, Calif.

Application March 6, 1948, Serial No. 144,937

Term of patent 14 years

(Cl. D34—5)

To all whom it may concern:

Be it known that I, Alfred H. Keast, a citizen of the United States, residing at San Francisco, State of California, have invented a new, original, and ornamental Design for a Game Board, of which the following is a specification, reference being had to the accompanying drawing, forming a part thereof.

Fig. 1 is a top plan view of a game board, showing my new design. The drawing is shaded to show color contrast.

Fig. 2 is a sectional view taken along line 2—2 of Fig. 1.

Fig. 3 is an end elevational view of the game board, as seen from the lower end, the opposite end being plain.

Fig. 4 is a reduced size side elevational view of the game board, its opposite sides being identical.

Fig. 5 is a reduced size sectional view taken along line 5—5 of Fig. 1.

The dominant features of my design reside in that portion shown in full lines of the drawing.

I claim:

The ornamental design for a game board, as shown and described.

ALFRED H. KEAST.
